[57] **CLAIM**

The ornamental design for a closure, as shown and described.

DESCRIPTION

FIG. 1 is a perspective view of a closure showing my new design;

FIG. 2 is a top plan view thereof;

FIG. 3 is a rear elevational view thereof;

FIG. 4 is a side elevational view, the undisclosed opposite side being a mirror image thereof;

FIG. 5 is a front elevational view thereof;

FIG. 6 is a perspective view of the closure with the top open;

FIG. 7 is a top plan view with the top open;

FIG. 8 is a rear elevational view with the top open;

FIG. 9 is a side elevational view with the top open, the undisclosed opposite side being a mirror image thereof; and,

FIG. 10 is a front elevational view with the top open.

The broken line showing of the hinge portion is for illustrative purposes only and forms no part of the claimed design.
